MIXING DEVICE

Thomas G. Gilley, Cranford, N. J., assignor to
Western Electric Company, Incorporated, New
York, N. Y., a corporation of New York

Application October 24, 1939, Serial No. 300,935

7 Claims. (Cl. 259—8)

This invention relates to a mixing device, and more particularly to a device for mixing liquids and/or solids.

In mixing various materials such as different liquids with each other, different solids with each other, or liquids with solids, such materials often require wide variations in treatment to bring about satisfactory mixtures.

An object of the invention is to provide a simple, efficient and highly variable device for mixing materials.

With this and other objects in view, the invention comprises a rotary element supporting a cup for materials to be mixed, apertured for the passage of materials between the cup and the element and adjustable relative to the axis of rotation of the element to vary the action of the cup and element on the materials.

Other objects and advantages will be apparent from the following detailed description when taken in conjunction with the accompanying drawing, wherein

Fig. 1 is a fragmentary vertical sectional view of the device, and

Fig. 2 is a fragmentary top plan view of the device.

In the present embodiment a rotary element 10, having a material working surface 11, is in the form of a disk-like table having a downwardly projecting embossed portion 12 rigidly fixed to a shaft 13 which extends through a bearing 14 of a bracket 15, upon which the portion 12 rests, to support the element. The bracket 15 is rigidly secured to the under side of a support 16 which may be a bench or the like. The bracket 15 has a second bearing portion 18 in which a shaft 19 is journaled, the latter being operatively connected to any suitable drive means (not shown) to drive the element 10, through a pinion 20 mounted upon the shaft 19 and a gear 21 mounted upon the shaft 13, in any desired constant or variable speed.

The support 16 is apertured for a receptacle 25, the latter completely surrounding the element 10 with a lower or bottom portion 26 tapering downwardly to an outlet 27, excepting adjacent the embossed portion 12 of the element, where the bottom portion 26 is bent upwardly in an open annular flange to allow free rotation of the element and prevent passage of the mixed materials, hereinafter described, from the receptacle other than through the outlet 27. Suitable means (not shown) may be connected to the outlet 27 to direct the material away from the receptacle. Angle members 30, arcuate in general contour,

are employed in the present embodiment to secure the receptacle 25 to the support 16.

A cup 32 has a bottom portion 33 providing a surface 34 for cooperating with the surface 11 of the rotary element 10 to treat materials. A central aperture 35 is formed in the bottom portion 33 of the cup for the passage of materials from the cup to the surface 11 and thus between the surfaces 11 and 34. A resilient handle 36 having one end fixed to the cup extends through a slotted member 37 carried by the wall of the receptacle 25 and through an aperture in the said wall to a position outside the receptacle, where a gripping portion 38 is formed for the manual adjustment of the cup on the element. A screw 40 or other suitable means is associated with the member 37 to engage the resilient handle 36 to lock it, with the cup, in any desired adjusted position. Suitable means is provided to vary the effect of the surfaces 11 and 34 on the material to be mixed by varying the force of the surfaces one toward another. In the present embodiment a weight 41 is slidably mounted on the resilient handle 36 by the aid of a longitudinally extending slot 42 through which the arm extends. A thumb screw 43 disposed in a threaded aperture in the weight 41 provides means for securing the weight to any desired position relative to the cup 32.

To illustrate the feeding of the materials to be mixed to the cup containers 45 and 46 are shown rigidly mounted upon an adjustable support 47. Suitable brackets 48 mounted upon the support 16 are bent laterally at their upper ends 35 for the resting of the adjustable support 47 thereon and provided with thumb screws 49 extending through elongate slots 50 in the adjustable support to lock the latter in any desired position. The containers 45 and 46, respectively, contain in the present embodiment a solid 51 and a liquid 52. It should be understood that solids or liquids may be disposed in both containers simultaneously or other containers may be provided to supply various types of solids or various types of liquids, or both, to the cup.

A supply line 55 having a control valve 56 therein feeds a controlled supply of the material 51 to the cup, while a supply line 57 having an adjustable valve 58 feeds a controlled supply of the liquid 52 to the cup.

During the operation of the device the shaft 19 is rotated by a suitable power source (not shown), causing rotation of the pinion 20, the gear 21, the shaft 13 and the element 10, the cup 32 remaining stationary, it being held by the

members 37 and 40. The materials 51 and 52, through the aid of the control valves 56 and 58, are fed to the cup in the proportions desired for the mixture and in suitable quantities to maintain a desired level of the materials in the cup. During rotation of the element the materials in the cup will pass through the aperture 35 to the surface 11 of the rotary element. The materials are then caused to move with the surface 11 but in so doing they must pass beneath the surface 34 of the cup. The surfaces 11 and 34, therefore, coact to mix the materials. The element 10 is rotated at a sufficient rate of speed to cause the mixed materials on the surface 11 to move outwardly by centrifugal force, but this movement is lower than the speed of rotation of the element, thus causing repeated movement of the material beneath the cup, adding new material to the surface as the previously deposited materials move outwardly toward the periphery of the rotary element, where they are thrown from the element onto the inner wall of the receptacle 25, after which the mixed materials pass downwardly to the outlet 27.

Various materials require various types of treatment to bring about satisfactory mixtures. The device may be conditioned for these variations by varying the position of the cup relative to the axis of rotation of the element and by varying the force of the coacting surfaces 11 and 34 one toward the other by adjustment of the weight 41 relative to the cup. For example, the cup may be disposed coaxially with the element, that is, the cup may be positioned so that its vertical center line and the axis of rotation of the element will be as one, at which position there will exist only a simple whirling action. In moving the cup from this position, at the axis of rotation of the element, toward the periphery of the element the effect of the surfaces 11 and 34 on the materials increases from the simple whirling action to a violent agitation, the latter existing when the cup is positioned adjacent the periphery of the rotary element. This is all due to the fact that the surface speed of the element increases from its minimum speed at its axis to its maximum speed at its periphery. Still wider variations may be accomplished in the action of the surfaces 11 and 34 on the materials by adjusting the weight 41 which may vary its effect on the surface 34 from substantially no added weight, when positioned adjacent the member 37, through increasing weights, as it is moved outwardly on the resilient handle 36, to its maximum effective weight when disposed adjacent the cup.

The support 47 for the containers 45 and 46 is adjusted when adjustment is made in the relative position of the cup and the element so that the materials from the containers may pass into the cup.

It will, therefore, be apparent that the rotary element and the cup provide cooperating working surfaces 11 and 34 to which materials may be fed in any suitable quantities through the control of the valves 56 and 58. Furthermore, means is provided, through the adjustment of the surface 34 relative to the axis of rotation of the element 10, to vary the action of the surfaces on the materials. The action of the surfaces on the materials is also varied by varying their positions relative to each other, that is, by applying a variable force to one of the elements to cause variation in the relative positions of the

surfaces, thus varying the action of the surfaces on the materials.

The embodiment of the invention herein disclosed is illustrative only and may be modified and departed from in many ways without departing from the spirit and scope of the invention as pointed out in and limited solely by the appended claims.

What is claimed is:

10. 1. A mixing device comprising a rotary element, a stationary cup for materials to be mixed apertured for the passage of the materials to the element, means to rotate the element to cause the materials from the cup to pass between the cup and the element, and a resilient member for varying the position of the cup relative to the axis of rotation of the element to vary the action of the cup and element on the materials.
20. 2. A mixing device comprising a rotary element, a stationary cup for materials to be mixed apertured for the passage of the materials to the element, means to rotate the element to cause the materials from the cup to pass between the cup and the element, a resilient member for varying the position of the cup relative to the axis of rotation of the element to vary the action of the cup and element on the materials, and variable weight means to further vary the action of the cup and element of the material.
30. 3. A mixing device comprising a rotary element, a stationary cup for materials to be mixed apertured for the passage of the materials to the element, means to rotate the element to cause the materials from the cup to pass between the cup and the element, a resilient member for varying the position of the cup relative to the axis of rotation of the element to vary the action of the cup and element on the materials, and variable weight means adjustably mounted on the resilient member to further vary the action of the cup and element on the material.
40. 4. A mixing device comprising a rotary element, means to rotate the element, a cup for materials to be mixed resting on the element and having an aperture therein for the passage of the materials between the cup and the element, and means to hold the cup against rotation to cause a surface thereof to coact with a surface of the element to mix the materials, a force resulting from the combined weight of the cup and the materials therein being utilized to effect the coacting surfaces in mixing the materials passing between the cup and the element.
50. 5. A mixing device comprising a rotary element, means to rotate the element, a cup for materials to be mixed resting on the element and having an aperture therein for the passage of the materials between the cup and the element, means to hold the cup against rotation to cause a surface thereof to coact with a surface of the element to mix the materials, a force resulting from the combined weight of the cup and the materials therein being utilized to effect the coacting surfaces in mixing the materials passing between the cup and the element, and means to vary the said force to vary the action of the coacting surfaces of the cup and the element on the materials.
60. 6. A mixing device comprising a rotary element, means to rotate the element, a cup for materials to be mixed resting on the element and having an aperture therein for the passage of the materials between the cup and the element, a force resulting from the combined weight of the cup and the materials therein being utilized to effect the coacting surfaces in mixing the materials passing between the cup and the element, and means to vary the said force to vary the action of the coacting surfaces of the cup and the element on the materials.
70. 7. A mixing device comprising a rotary element, means to rotate the element, a cup for materials to be mixed resting on the element and having an aperture therein for the passage of the materials between the cup and the element, a force resulting from the combined weight of the cup and the materials therein being utilized to effect the coacting surfaces in mixing the materials passing between the cup and the element, and means to vary the said force to vary the action of the coacting surfaces of the cup and the element on the materials.

lized to effect coacting surfaces of the cup and element in mixing the materials passing therebetween, and means to hold the cup against rotation at various positions on the element to vary the action of the coacting surfaces of the cup and element on the materials.

7. A mixing device comprising a rotary element, means to rotate the element, a cup for materials to be mixed resting on the element and having an aperture therein for the passage of the materials between the cup and the element, means to hold the cup against rotation to cause a surface thereof to coact with a surface

5 of the element to mix the materials, a force resulting from the combined weight of the cup and the materials therein being utilized to effect the coacting surfaces in mixing the materials passing between the cup and the element, and separate means to vary the action of the cup and element on the materials, one means varying the force of the surface of the cup toward the surface of the element and another means varying 10 the position of the cup relative to the axis of rotation of the element.
